UNITED STATES PATENT OFFICE.

LAWRENCE H. BAKER, OF BIRMINGHAM, ALABAMA.

ADVERTISING-CABINET.

1,030,862.

Specification of Letters Patent.

Patented July 2, 1912.

Application filed September 8, 1911. Serial No. 648,321.

To all whom it may concern:

Be it known that I, LAWRENCE H. BAKER, a citizen of the United States of America, residing at Birmingham, in the county of 5 Jefferson and State of Alabama, have invented certain new and useful Improvements in Advertising-Cabinets, of which the following is a specification.

My invention relates to certain improvements in advertising means for use in connection with a toilet cabinet and consists in the provision of a transparent display film or belt which is adapted to be turned in feeding the paper, in combination with a 15 means for flashing on a light to display the advertisements only when the apparatus is in use.

A further object of my invention is the provision of a novel and effective means to 20 insure the light being cut out except when the cabinet is in use.

A still further object is to facilitate the exchange of advertising matter and the repair of the apparatus by mounting the advertising apparatus in a frame-work which 25 is detachable from the cabinet.

My invention further comprises the details of construction and arrangement of parts hereinafter more particularly described and claimed, reference being had to the accompanying drawings, in which:—

Figure 1 is a vertical cross-sectional elevation through the center of the cabinet. Fig. 2 is a front elevation of Fig. 1 partly broken away. Fig. 3 is a detail view of the advertising apparatus detached, and Fig. 4 is a front elevation of Fig. 3 with the display belt and battery removed. Fig. 5 is a detail view of the circuit controlling device.

Similar reference numerals refer to similar parts throughout the drawings.

The cabinet is formed preferably of an elongated metallic casing having a front wall 1 provided with a glass covered opening 2 near its bottom portion and having a top 3 and a side door mounted on hinges 4. The top is provided with a holder 5 to receive a slide 6 which carries a pair of hangers 7 in which the roll 8 for the toilet paper 9 is journaled. In the lower portion of the cabinet I insert a metallic frame-work 10 having rolls 11 and 12 journaled at its upper corners and provided also with a slot 13 which receives the axes of an idler roll

14. At the lower front corner of the frame 55 10 I mount a roll 15 provided with a felt or like cover, and at the rear lower corner of the frame-work I mount two rolls 17 and 18, which likewise have felt covers. The roll 18 is set in an inclined slot 19 formed 60 in a rear extension 20 of the frame and this roll is forced downwardly in this slot and against the roll 17 by means of a spring 21, which is fastened on a pin 22 and bent around a pin 23 with its free end engaging 65 the axle 24 of the roll 18. This insures an effective frictional grip between the rolls 17 and 18, which are the rolls utilized to feed the paper, which, it will be noted, is passed under the idler 14 and over the pulley 12 70 and between the pulleys 17 and 18, below which it passes out through a slot 25 at the bottom of the cabinet. An endless display belt 26, preferably of transparent material, is provided with a series of transparent display advertisements and the belt, which is 75 endless, passes continuously around the pulleys 11, 12, 15 and 17 and is held in proper tension by the idler 14.

The frame-work is provided with a cross 80 support 27 on which is mounted a dry battery 28. A spring clip 29 holds the battery against accidental displacement, holding it pressed against a cross plate 50. The clip is bolted at its center to bar 51. I mount an 85 electric light bulb 30 in the cabinet opposite the opening 2, the socket 31 for the bulb being attached to a back plate 52 and being connected by wire 32 with a contact post 53 on plate 50. This post is adapted to engage 90 the terminal 33 of the battery, the other terminal of which will engage with a contact 34 from which the wire 35 leads to a contact post 36 that projects through an opening in the lower side wall of the frame 95 from which it is suitably insulated. At its outer end this post carries the flattened contact plate 37. A spring contact 38 is hinged to a pin 39 mounted in the frame but insulated therefrom, and normally hangs by 100 gravity away from the contact 37. Pin 39 projects through the frame and has connected to its inner end a wire 40 which leads to the lamp socket. The operating shaft 41 for the roller 17 is adapted to extend through 105 the side wall of the cabinet and there be connected to a milled wheel by which it may be turned. Between the casing and the ad-

jacent end of the frame 10, I mount upon this shaft 41 a contact make and break device 43, which is held in frictional engagement with the shaft 41 by means of a screw 5 44 which draws it together about the shaft.

When the shaft is turned in the proper direction to feed out the paper, the make and break device 43 (Fig. 5) will be swung upwardly engaging the spring 38 and forcing it upwardly and into position to engage the contact 37, or to the dotted line position shown in Fig. 3. When this takes place, the circuit to the lamp is closed from the terminal 34 through the wire 35 to the contact 10 post 36, spring 38, pin 39, and wire 40 and back through wire 32 and terminal 53 to the battery. As long as the wheel 42 is grasped and is being turned, this circuit will be held closed, but the moment the wheel is released 15 20 by the hand of the operator, the contact maker 43 drops by gravity away from the spring 38 and breaks the lamp circuit. By this means the lamp is flashed on only while the apparatus is in use and a minimum of 25 current is consumed. Should the battery need replacing or any part of the advertising apparatus become defective, or require exchange or renewal, the end door of the 30 casing can be quickly opened and the entire advertising apparatus withdrawn and a new apparatus substituted without delay. This advantage is of particular importance where it is desired to frequently replace the display belts.

35 The frame 10 is provided with extensions 45, 46, and 47, to give it a close fit with the walls of the casing. Where convenient, electric current for the lamp may be delivered from house wires to the contacts and the dry 40 battery eliminated. Also the form and arrangement of the circuit connections may be varied so long as a circuit is automatically broken the moment the pressure of the operator's hand is withdrawn from the wheel 42.

45 In order to insure the positive breaking of the circuit connections to the lamp the moment the hand wheel is released, I provide an insulated stop 49 about which the contact 38 is bent with a spring action by 50 the make and break device 43 (Fig. 3). By thus bending the spring contact 38 under tension, it will require the friction of the turning pressure from the hand wheel on the axle 41 to hold the spring in position to 55 close the circuit.

It will be noted that in this construction the toilet paper does not pass between the window 2 and the lamp 30, which is the case in the patent to Wilkes No. 898,949.

60 In order to enable one to easily inspect the amount of paper on the roll without necessitating the opening of the casing, I provide a glass covered opening 54 in the side of the casing so positioned that the paper roll is 65 visible.

Having thus described my invention, what I claim as new and desire to secure by Letters Patent, is:

1. The combination of a cabinet having a transparent window, a body of paper supported therein, a series of guide rollers located therein, an advertisement carrying strip passing around some of said rollers, an operating hand wheel connected to one of said rollers and adapted to effect the feeding of said paper from said cabinet, an electric lamp, an electric circuit for said lamp, and circuit controlling means comprising a circuit closer in frictional engagement with said hand wheel and adapted to be moved thereby to close said circuit when the hand wheel is being turned to feed the paper, and means to automatically and positively move said circuit closer to open the circuit as soon as pressure on the hand wheel is released. 70 75 80 85

2. The combination of a cabinet having a transparent window, a roll of paper movably supported in the upper part of said cabinet, a detachable advertising apparatus 90 disposed in said cabinet below said paper roll and comprising an endless advertisement carrying strip, a plurality of guide rollers therein, means to simultaneously advance said strip and feed said paper from 95 said cabinet, a lamp to display the advertisements opposite said window, electric circuits for the lamp, a make and break switch in said circuits, means to close said switch by frictional engagement with the 100 paper feed means while being operated, and means to automatically open said switch as soon as said feed mechanism is released by the hand of the operator, substantially as described. 105

3. The combination with a cabinet having a transparent window, of a roll of paper supported therein, and an advertising medium comprising a frame-work detachably mounted in said cabinet, rollers journaled 110 in said frame-work, a storage battery and an electric lamp connected to said frame-work, an advertisement strip passing around some of said rollers, one of which has an axle projecting through said cabinet, a hand 115 wheel connected to said axle and adapted to turn a roller, means co-operating with said latter roller to turn the advertisement strip and feed said paper through an opening in the cabinet, a normally open electric circuit 120 for said lamp, a circuit closer movable by frictional engagement with parts operable with the hand wheel to close said circuit as long as pressure is applied to said hand wheel to turn it, and means to disengage 125 said circuit closer when pressure on the hand wheel ceases. 130

4. A display cabinet comprising a front transparent window, a roll of paper movably supported near the upper end of the 130

cabinet, a number of feed rollers rotatably mounted in the cabinet and disposed below said paper roll, a transparent advertisement strip adapted to pass around two or more of 5 said rolls and in front of said window, an electric lamp disposed in the cabinet opposite said window, one part of said strip being arranged between said lamp and window, an idler roller which rests on said strip 10 and maintains its tension about said rollers, the paper from said roll being passed under said idler roller and down behind said lamp and between two or more rollers, means to cause said latter rollers to grip said paper 15 strip and also said advertisement strip, a

hand wheel operable from without the cabinet and connected to one of said latter rollers, a normally open electric circuit for said lamp, means operable by said hand wheel which close said lamp circuit only while the 20 wheel is being operated, and spring means to positively break said circuit when the hand wheel is released.

In testimony whereof I affix my signature in presence of two witnesses.

LAWRENCE H. BAKER.
